UNITED STATES PATENT OFFICE.

JOHN FORSEBERG, OF CHICAGO, ILLINOIS.

TRACK RAISING AND SHIFTING APPARATUS.

Application filed September 2, 1922. Serial No. 586,009.

To all whom it may concern:

Be it known that I, JOHN FORSEBERG, a citizen of the United States, residing at Chicago, in the county of Cook and State of Illinois, have invented certain new and useful Improvements in Track Raising and Shifting Apparatus, of which the following is a specification.

My invention relates to apparatus for raising and shifting track.

The invention contemplates the provision of a supporting structure, preferably mounted upon wheels adapted to run upon the track, and which is anchored to the track; and one of the objects of my invention is the provision of a lifting member, the lower end of which is adapted to anchor itself in the track bed, so associated with the supporting structure in combination with suitable mechanism whereby movement of the lifting member relative to the supporting structure may be effected generally in a direction lengthwise of the lifting member and a section of the track raised either partly or entirely out of its bed so that the material forming the track bed may be placed under and around the ties and tamped in the usual manner.

A further object of my invention is the provision of apparatus whereby a section of track may be picked up and shifted bodily to one side or the other, or lengthwise, if desired; and, to this end the invention contemplates the provision of a lifting member pivotally and slidably connected to the supporting structure in such manner that the lifting member may be placed obliquely or at an angle relative to the road bed, whereby upon movement of the lifting member relative to the supporting structure being effected in a direction lengthwise of the member, the supporting structure and the section of track to which it is anchored will be bodily raised and shifted to one side or the other, or in a lengthwise direction, depending upon the direction in which the lifting member is inclined.

The means for pivotally and slidably connecting the lifting member with the supporting structure preferably includes a frame pivotally connected to the supporting structure and with which the lifting member is slidably associated; and, a further object of my invention is the provision of novel means for effecting movement of the lifting member relative to the frame and supporting

structure, said means preferably including a rack bar formed on or fixed to the lifting member with which a gear journaled in the frame is adapted to mesh, any suitable means, for example, a crank, being provided to drive said gear.

A further object of my invention is the provision of means for holding the pivoted frame in a vertical position which may be accomplished by providing one or more readily detachable brace rods extending diagonally from the frame to the supporting structure; this feature of the invention being particularly useful when it is desired to raise relatively low sections of track so that filling material may be worked under the ties and tamped.

Another object of my invention is the provision of means for holding the lifting member against retrograde movement relative to the supporting structure after a section of track has been raised or shifted while workmen fill in material around the ties and tamp it, this preferably being accomplished by providing a pawl on the frame which is adapted to engage the teeth of the rack bar.

A further object of my invention is to provide an arrangement whereby the weight of the track and the supporting structure anchored to it will be utilized to aid in shifting the track in the direction desired; and, to this end the pivotal connection between the frame supporting the lifting member and the main supporting structure is offset to one side or the other of the lifting member, depending upon the direction in which it is desired to shift the track; thus the longitudinal thrust or strain to which the lifting member is subjected is eccentrically disposed relative to the pivotal connection to that side of the pivotal connection to which the track is to be shifted and materially aids in swinging or shifting the track in the desired direction.

A further object of my invention is the provision of one or more stay means extending generally in the direction of the lifting member from the supporting structure to the track so that distortion of the supporting structure under the load of the track will be effectively prevented; each of said means preferably including a pair of stay rods connected together by a turnbuckle the outer end of one rod being readily detachably connected to one side of the supporting structure and the opposite end of

the other rod being formed with a hook adapted to engage the head of the rail on the opposite side of the track.

A further object of my invention is the provision of novel means to anchor the supporting structure to the track, said means preferably comprising several pairs of clamping members formed at their lower ends with complementary hooks adapted to embrace the head of the rail and being adjustably connected at their upper ends by a threaded stud to the supporting structure, a slip ring surrounding each pair of clamping members to hold them in binding engagement with the head of the rail.

A further object of my invention is the provision of a relatively long supporting structure, preferably mounted upon wheels adapted to run upon the track, on which several lifting members are arranged in spaced relation so that a relatively long section of track may be handled at one time.

The invention consists in the novel constructions, arrangements and devices to be hereinafter described and claimed for carrying out the above stated objects and such other objects as will appear from the following description of certain preferred embodiments illustrated in the accompanying drawings, wherein—

Fig. 1 is a plan view of an apparatus anchored to a section of track and embodying the principles of my invention;

Fig. 2 is a side elevational view of the apparatus; Fig. 3 is a detail view of one of the means for anchoring the supporting structure to the track;

Fig. 4 is an end elevational view of the apparatus;

Fig. 5 is a vertical sectional view, on an enlarged scale, of the supporting frame for the lifting member, taken on the line 5—5 of Fig. 6;

Fig. 6 is a transverse sectional view taken on the line 6—6 of Fig. 5;

Fig. 7 is a plan view of a modified form of apparatus anchored to a section of track and also embodying the principles of my invention;

Fig. 8 is an end elevational view of a fragmentary portion of the apparatus illustrated in Fig. 7;

Fig. 9 is a sectional view taken on the line 9—9 of Fig. 7; and

Fig. 10 is a side elevational view, on a reduced scale, of a relatively long supporting structure with which a plurality of lifting members are associated.

Like characters of reference designate like parts in the several views.

Referring first to Figs. 1 to 6, inclusive, of the drawings, the supporting structure includes a pair of longitudinally extending foundation members 10 connected by transversely extending members 11 to form a

rectangular frame which is preferably mounted upon axles 12 on which are journaled wheels 13 adapted to run upon the rails 14 of the track to be lifted or shifted. A plurality of members 15 extends transversely across the foundation members 10, being secured thereto in any desired manner and being connected at their ends to longitudinally extending members 16.

The supporting structure thus formed may be anchored to the track in any desired manner, but I prefer to employ several pairs of clamping members 17, one pair being shown in detail in Fig. 3. The lower ends of the clamping members are bent around to form hooks 17^a adapted to engage the under sides of the head of the rail and the upper ends are apertured so that the eye 18^a of a threaded stud 18 may be passed therethrough. Certain of the members 15 are provided adjacent each end with suitable apertures through which the respective studs 18 may extend, a nut, preferably in the form of a hand wheel 19, being threaded on the upper ends of each of the studs. A slip ring 20 surrounds each pair of clamping members 17, and, as this ring is relatively heavy, it will be obvious that, once the clamping members are brought into operative engagement with the head of the rail, the ring will readily slip down and effectively hold the clamping members in engagement with the rail head.

In the accompanying drawings, I have shown a pair of lifting members 21 each of which extends through a frame, designated generally by the reference character 22. When two of the lifting members are employed, they may be of relatively light construction and, therefore, are easier to handle. The two members are ordinarily operated in unison. It will be obvious that one relatively heavy member might readily be substituted for the two members.

Each of the frames 22 comprises a pair of spaced plates 23 secured together by rivets 24 surrounded, respectively, by spacing bushings 25. On one side of the lifting member 21 a rack bar 26 is provided, the width of which is somewhat less than that of the bar 21, see Fig. 6. On the same side of the lifting member flanged rollers 27 are journaled between the plates 23, the peripheries of the flanges of said rollers being adapted to bear against the smooth portions of the adjacent side of the lifting member 21. On the opposite side of the lifting member rollers 28 also journaled between the plates 23 are provided to bear against the adjacent side of the lifting member. A short shaft 29 is journaled in the plates 23 and has keyed thereto a gear 30 the teeth of which are adapted to mesh with the teeth of the rack bar 26. The shaft 29 may be turned in any desired manner, for example, by a crank or lever 31. Each of the frames 22 is provided

with bearings 32 and 33 through either of which a pivot shaft 34 may extend, the shaft 34 being supported in any of the bearings 35, 35^a or 35^b provided in the adjacent transversely extending members 15. It will be obvious, therefore, that the lifting members 21 are pivotally and slidably associated with the supporting structure.

In Fig. 5 the shaft 34 is shown as extending through the bearings 32 of the frame 22 and in Fig. 4 said shaft is also shown as extending through the bearings 35^a of the frame members 15. It will be noted that the bearings 32 are off-set to the left of the lifting member, as viewed in Figs. 4 and 5, consequently, the frame 22 and the lifting member tend to tilt in a clockwise direction which is desirable when it is intended to shift the track to the right, having reference to Fig. 4. When it is desired to shift the track in that direction, the frame 22 is inclined substantially as shown in the dotted line position in Fig. 4. Upon turning the shaft 29 in a clockwise direction, movement of the lifting member relative to the supporting structure will be effected in a direction longitudinal of said member. After all lost motion has been taken up and the lower end of the lifting member has anchored itself in the track bed, the supporting structure and the track anchored to it will be forced or shifted to the right. It will be understood that the lower end of the lifting member is placed between the ties of the track and this end of said member may be provided with a plurality of laterally projecting feet 21^a to prevent the lifting member from working itself too far into the track bed. Shifting of the track to the right may be continued until the track has been shifted to such an extent that the inner side of the left rail bears against the adjacent side of the member 21. When that occurs, the lifting member must be re-positioned in order to continue the shifting operation. It will be obvious that the track may be shifted a greater distance when the shaft 34 is placed in the bearings 35^b before it is necessary to re-position the lifting member. When it is desired to shift a track to the left, the shaft 34 is inserted through the bearings 33 of the frame 22, consequently, the frame and lifting member tend to tilt in an anti-clockwise direction. The extent to which the track is to be shifted to the left will determine whether it is best to insert the shaft 34 in the bearings 35^a or 35. With this arrangement, therefore, it will be apparent that advantage is taken of the eccentrically disposed longitudinal thrust or strain to which the lifting member is subjected to aid in shifting the track in the direction desired.

When the track is being shifted, the supporting structure is subjected to a very considerable strain and is likely to be distorted

unless bracing means are provided which extend generally in the same direction as the lifting member from one side of the supporting structure to the opposite side of the track. As the supporting structure must be shifted more or less frequently along the track, it is desirable that the bracing means be conveniently attached to or detached from the supporting structure and track. In the drawings, I have shown a stud 36 rigidly connected to and extending from each end of each of the longitudinal frame members 16. The bracing means may comprise a pair of rods 37 and 38 connected together by a turn buckle 39, the upper end of the rod 38 being formed with an eye 38^a adapted to slip over the end of one of the studs 36 and the lower end of the rod 37 being formed with a hook portion 37^a adapted to slip into holding engagement with the head of the rail on the opposite side of the track. When the track is to be shifted to the right, the bracing means are positioned as shown in full lines in Figs. 1 and 4, and, when it is to be shifted to the left, the bracing means are reversed, being positioned, in that case, as shown in dotted lines in Fig. 4.

The apparatus is very useful in raising relatively low sections of track and, when it is used for that purpose, the shaft 34 is preferably inserted through the bearings 35^a so as to center the load on the lifting member. In that case, it is desirable to prevent any oscillating movement of the frame 22 on the shaft 34, and I, therefore, provide one or more brace bars 40 extending diagonally from the supporting structure to the frame 22, substantially as shown in Figs. 1 and 4. The lower ends of these bars may be formed with hooks adapted to project through eye members 41 attached to the longitudinally extending frame members 10 and the upper ends of said bars formed with hooks adapted to slip over a bolt or rivet 42 attached to the plates 23 of the frame 22. When the apparatus is used for lifting the track, it is also desirable to provide means for preventing retrograde movement of the lifting member relative to the frame and to this end a pawl 43, see Fig. 5, may be pivoted between the plates 23 which is normally urged into engagement with the teeth of the rack bar 26 by a spring 44. The pawl may be disengaged from the rack bar teeth by pulling on the wire or rod 45.

In Figs. 7 to 9, inclusive, I have illustrated my invention as embodied in apparatus adapted to shift a section of track either sidewise or longitudinally. In these views the supporting structure includes longitudinally extending foundation members 10^a connected to transversely extending members 11^a to form a rectangular frame. The extremities of the members 11^a are preferably connected to longitudinally extending

frame members 16^a. The members 11^a are provided with transversely extending slots 46 which may be reinforced by a casting 47. Bearing blocks 48 are slidably mounted in 5 the respective slots 46, said blocks being provided with laterally projecting flanges 49, the flanges 11^b of the channel members 11^a and the flanges 49, respectively, having registering perforations so that vertically disposed pins 50 may be dropped therethrough to secure the bearing blocks at any one of several positions in the slots. Frame 22 supporting the lifting member 21 is carried by 10 an auxiliary longitudinally extending frame 15 consisting of a pair of channel members 51 bolted at their extremities to spacing blocks 52. Stub shafts 52^a extend from the blocks 52 and are journaled in bearing blocks 48, respectively. The members 51 are provided 20 with slots 53 reinforced by a casting 53^a, bearing blocks 54 being slidably disposed in the respective slots 52. The bearing blocks 54 are provided with horizontal flanges 55, the flanges 51^a of the members 51 and the 25 flanges 55, respectively, being provided with registering apertures adapted to receive pins 56 so that the bearing blocks 54 may be secured in any one of several positions with respect to the auxiliary frame. The shaft 30 34 on which the frame 22 rocks is journaled in the bearing blocks 54. It will be seen that the connection between the frame 22 and the auxiliary frame is substantially the same as that between the auxiliary frame and the 35 members 11^a, in the particular embodiment shown, the auxiliary frame being adapted to rock on a longitudinally extending substantially horizontal axis while the frame 22 is free to rock on a transversely extending substantially horizontal axis. In using 40 this form of apparatus for shifting a section of track lengthwise, it may be necessary to remove one or two ties from under the rails so as to permit the lifting member to be 45 positioned at the desired inclination, but the removal of the ties is a comparatively simple matter.

In Fig. 10 of the drawing I have illustrated the principles of my invention as 50 embodied in apparatus adapted to lift or shift a relatively long section of track. A plurality of pairs of lifting members are mounted in spaced relation on a suitable supporting structure which, in this case, may 55 be a relatively long flat car, or the like. The several pairs of lifting members may be placed fifteen or twenty feet apart, and approximately sixty or eighty feet of track lifted or shifted without moving the car 60 from one place to another.

I do not intend to limit my invention to the details of construction described and claimed except only in so far as certain of the appended claims are specifically so limited, as it will be obvious to those skilled in

the art, that modifications may be made without departing from the spirit of the invention.

I claim:

1. Apparatus of the class described comprising a supporting structure, means to anchor said structure to a section of track, a frame pivotally connected to said structure, a lifting member slidably associated with said frame, means for effecting movement of said member relative to said frame, and bracing means extending from said frame to said structure and adapted to secure said frame in a substantially vertical position for the purpose specified. 70

2. Apparatus of the class described comprising a supporting structure, means to anchor said structure to a section of track, a frame pivotally connected to said structure, a lifting member slidably associated with said frame, means for effecting movement of said member relative to said frame, and readily detachable bracing means adapted to secure said frame when in a substantially vertical position to said structure. 85

3. Apparatus of the class described comprising supporting means adapted to be anchored to a section of track, lifting means slidably carried by said supporting means, a rack bar fixed to one of said means, a gear journaled in the other of said means and in mesh with said rack bar, and a pawl carried by said last-mentioned means and adapted to engage said rack bar, for the purpose specified. 90

4. Apparatus of the class described comprising a supporting structure, means to anchor said structure to a section of track, a lifting member slidably carried by said structure and provided with a rack bar, a gear journaled in said supporting structure and in mesh with said rack bar, and a pawl carried by said supporting structure and adapted to engage said rack bar, for the purpose specified. 100

5. Apparatus of the class described comprising a supporting structure, means to anchor said structure to a section of track, a frame pivotally connected to said structure, means to secure said frame when in a substantially vertical position to said structure, a lifting member slidably associated with said frame, means for effecting movement of said member relative to said frame in a direction lengthwise of said member, and means for holding said member against retrograde movement relative to said frame. 115

6. Apparatus of the class described comprising a supporting structure, means to anchor said structure to a section of track, a frame pivotally connected to said structure, means to secure said frame when in a substantially vertical position to said structure, a lifting member slidably associated 125

- with said frame and provided with a rack bar, a gear journaled in said frame and in mesh with said rack bar, and a pawl carried by said frame and adapted to engage 5 said rack bar, for the purpose specified.
7. Apparatus of the class described comprising a supporting structure, means to anchor said structure to a section of track, a lifting member, means pivotally and slidably connecting said member with said structure, and means for effecting movement of said member relative to said structure in a direction lengthwise of said member, the pivotal connection between said member and 10 said structure being such that it may be off-set to one side or the other of the member, for the purpose specified.
8. Apparatus of the class described comprising a supporting structure, means to anchor said structure to a section of track, a frame pivotally connected to said structure, a lifting member slidably associated 15 with said frame, and means for effecting movement of said member relative to said frame, the pivotal connection between said frame and said structure being such that it may be off-set to one side or the other of the lifting member, for the purpose specified.
9. Apparatus of the class described comprising a supporting structure, means to anchor said structure to a section of track, a lifting member, means pivotally and slidably connecting said member with said structure whereby said member may be positioned 20 at an angle relative to the track bed, means for effecting movement of said member relative to said structure in a direction lengthwise of said member, and stay means extending generally in the direction of said lifting member from said structure to the track.
10. Apparatus of the class described comprising a supporting structure, means to anchor said structure to a section of track, a lifting member, means pivotally and slidably connecting said member with said structure whereby said member may be positioned 25 at an angle relative to the track bed, means for effecting movement of said member relative to said structure in a direction lengthwise of said member, and adjustable stay rods extending generally in the direction of said lifting member from said structure to the track.
11. Apparatus of the class described comprising a supporting structure, means to anchor said structure to a section of track, a lifting member, means pivotally and slidably connecting said member with said structure whereby said member may be positioned 30 at an angle relative to the track bed, means for effecting movement of said member relative to said structure in a direction lengthwise of said member, and adjustable stay rods extending generally in the direction of said lifting member, and adjustable 35 stay rods extending generally in the direction of said member.
12. Apparatus of the class described comprising a supporting structure, means to anchor said structure to a section of track, a lifting member, means pivotally and slidably connecting said member with said structure whereby said member may be positioned 40 at an angle relative to the track bed, means for effecting movement of said member relative to said structure in a direction lengthwise of said member, and stay means extending generally in the direction of said lifting member and comprising a pair of rods fastened together by a turn-buckle, said last mentioned means at one end being adapted to be connected to one side of said structure and at the other end being adapted 45 to hook over the head of the rail on the opposite side of the track.
13. Apparatus of the class described comprising a supporting structure, a lifting member associated with said structure, means for effecting movement of said member relative to said structure in a direction lengthwise of said member, and means to anchor said structure at several places to a section of track, each of said last-mentioned means 50 comprising a pair of clamping members the lower ends of which are formed so as to grip the head of a rail, means connecting the upper ends of said clamping members with said structure, and a slip ring surrounding 55 said clamping members, for the purpose specified.
14. Apparatus of the class described comprising a supporting structure, a lifting member associated with said structure, means for effecting movement of said member relative to said structure in a direction lengthwise of said member, and means to anchor said structure at several places to a section of track, each of said last-mentioned 60 means comprising a pair of clamping members the lower ends of which are formed so as to grip the head of a rail, means adjustably connecting the upper ends of said clamping members with said structure, and a slip ring surrounding 65 said clamping members, for the purpose specified.
15. Apparatus of the class described comprising a supporting structure including transversely extending supporting means 70 provided with a plurality of longitudinally disposed bearings, means to anchor said structure to a section of track, a frame, a lifting member slidably associated with said frame, means for effecting movement of 75 said member relative to said frame, and a shaft extending through said frame and adapted to be inserted in any one of said bearings.
16. Apparatus of the class described com- 80

prising a supporting structure, means to anchor said structure to a section of track, a lifting member, means pivotally and slidably connecting said member with said structure and so adapted that said member may be positioned obliquely transversely or longitudinally with respect to the track, and means for effecting movement of said member relative to said structure in a direction lengthwise of said member.

17. Apparatus of the class described comprising a supporting structure, means to anchor said structure to a section of track, a frame, means connecting said frame with said structure so adapted that said frame may rock transversely or longitudinally with respect to the track, a lifting member slidably associated with said frame, and means

for effecting movement of said member relative to said frame.

18. Apparatus of the class described comprising a supporting structure, means to anchor said structure to a section of track, an auxiliary frame slidably connected to said structure and pivoted to swing about a substantially horizontal axis, a second frame slidably connected to said auxiliary frame and pivoted to swing about a substantially horizontal axis which is substantially at right angles with respect to said first-mentioned axis, a lifting member slidably associated with said second frame, and means for effecting movement of said member relative to said second frame.

JOHN FORSBERG.
